VELOCITY MODULATION DEVICES

Emile Touraton, Claude Dumousseau, and René Zwobada, Paris, France, assignors to International Standard Electric Corporation, New York, N. Y., a corporation of Delaware

Application January 15, 1948, Serial No. 2,355

Claims priority, application France January 17, 1947

7 Claims. (Cl. 315—6)

The present invention relates to velocity modulation tubes.

One object of the present invention is a velocity modulation tube of the reflex type, in which progressive wave guides are used instead of resonating volumes.

Other objects and features of the present invention will be apparent from the following description of an embodiment made in relation to the drawings in which:

Fig. 1 shows in cross-section a velocity modulation tube incorporating features of the invention.

Fig. 2 is a vertical section taken along the line 2—2 of Figure 1.

Figs. 3 and 4 show curves useful for understanding the operation of the velocity modulation tubes of the present invention, and

Figs. 5 to 7 show other embodiments of the invention.

Referring now to Fig. 1, this figure shows a velocity modulation tube incorporating features of the invention which comprises a wave guide 1 and a wave guide 2 brought to a given potential and through which a flat beam of electrons, emitted by an elongated cathode 3, flows in succession. The flat electron beam is reflected by the decelerating field produced by a reflector 4 and successively flows through wave guide 2 and wave guide 1 from the reflector, and is finally attracted by the bottom part of guide 1 as shown in Figure 2 by a dotted line.

The dimensions and the potentials of the various elements are chosen in such a way that the transit time of the electrons in each guide be equal to $T/4$, T being the period of the oscillation, which varies according to the potential of the reflector. The total value of the transit time for both guides is therefore $T/2$. It is also necessary that the time elapsing between two successive passages of the unmodulated electrons in the centre of guide No. 1 be equal to $KT + T/4$, where K is an integer.

On Fig. 1 the waves travel in the guides from right to left. Wave guide 1 is terminated on the left by a load 6 which must be equal to the characteristic impedance of the guide. Guide 2 is terminated on the right in its characteristic impedance 7. The left end of guide 2 feeds the right end of guide 1 through a connection without reflection, in such a way that at two points 8 and 9 of the same vertical section of guides 1 and 2, the wave travelling in guide 1 is lagging one fourth of a period behind the wave travelling in guide 2.

It will be assumed that the electron beam is suitably bunched at its second passage in guide 2 and that the high-frequency potential in the guide is such that the bunches of electrons of the beam be retarded. These bunches of electrons take one quarter of a period to go from guide 2 to guide 1. Since the wave which travels in guide 1 lags one-fourth of a period behind the wave which travels in guide 2, the bunches of electrons are slowed down again in guide 1. The beam will therefore give up energy to guide 2 and then to guide 1 and it is possible to pick up this energy. The time of travel in the two guides is sufficiently short so that the electrons remain grouped together.

2

Fig. 3 shows the high-frequency potentials of the guides, the distance from the origin of each guide being given along the abscissa and the high-frequency potentials of the guides in the ordinates.

5 The potential in each point of guide 1 is equal to the sum of the potential prevailing at the right end of guide 2 plus an additional potential proportional to the distance from this point to the beginning of guide 1 (see Fig. 3 curve 10).

10 The potential in each point of guide 2 is proportional to the distance from this point to the left end of the guide (see Fig. 3, curve 11).

15 Fig. 4 shows the high frequency potential in both guides in vectorial form, showing the lag of one fourth of a period of the potential of guide 1 (shown by vector 12) behind the potential of guide 2 (shown by vector 13).

During its travel the electron beam is first modulated by the potential of guide 1 and one fourth of a period later it is modulated by the potential of guide 2, which is leading ahead of potential of guide 1 by one fourth of a period. The modulation due to guide 2 is therefore in phase opposition to the modulation due to guide 1.

20 The resulting electron modulation is equivalent to a modulation by a single potential, in phase with potential of guide 1 and equal in absolute value to the difference of the absolute values of the potential of guides 1 and 2. Since this difference is constant for all the points of the guide, as may be seen on Fig. 3, the electron beam is uniformly modulated on the whole length of the guides.

25 The potential of the reflector is adjusted so that the oscillation which takes place has a given wavelength. In the above-mentioned conditions, if the reflector potential is slightly changed, for instance in such a way that the transit time be increased, there will be a drift of the oscillations towards longer wavelengths so that the number of periods included in the transit time of the electrons remain the same. It will thus be possible to vary the frequency of oscillation of the tube by a mere change in the potential of the reflector. This frequency drift may be large, for instance ten per cent of the fundamental frequency.

30 Fig. 5 shows a top view of a velocity modulated tube incorporating features of the invention and Fig. 6 a sectional view along thereof. Inside a glass vessel, two guides 14 and 15 are connected end to end, and wound spirally. They have a common wall and are therefore at the same potential, their length is equal to $(K + \frac{1}{4}l)$, l being a value close to the oscillation wavelength of the tube and K an integer.

35 Cathode 17 and the focussing system 18 of the cathode ray beam are external to the spirals. Reflector 19 is located inside the spiral and its shape is adapted to reflect the beam in a given direction.

40 With reference to Figure 7 there is shown a velocity modulation tube incorporating a further embodiment of this invention. Helically wound wave guide of two turns is used in this embodiment. The helically wound wave guide forms two wave guides 20 and 21, one above the other between a cathode 22 and a reflector 23 each of which is formed as a single turn of a helix.

45 Although the present invention has been described in relation to embodiments it is clear that these embodiments may be modified without departing from the scope of the invention.

50 We claim:

55 1. A high frequency electronic device comprising an elongated cathode electrode, an elongated reflector electrode whose length runs in substantially the same direction as that of the cathode electrode, said electrodes being spaced apart a given distance throughout their length, wave guide lengths disposed adjacent each other in overlapping relation between said electrodes and spaced

therefrom, said wave guide lengths being connected to each other and having openings therethrough substantially co-extensive with said electrodes and in alignment therewith, the transit time of an electron between corresponding points in said openings being a quarter of a period at the operating frequency, the distance between said corresponding points as measured through the connected wave guide lengths being effectively electrically a quarter wavelength at the same frequency, and means effectively terminating said wave guide lengths in their characteristic impedance, to thereby prevent standing waves.

2. A high frequency electronic device according to claim 1, wherein said wave guide lengths comprise a continuous wave guide structure.

3. A high frequency electronic device according to claim 1, wherein said electrodes and said wave guide lengths are circularly disposed.

4. A high frequency electronic device according to claim 3, wherein said electrodes and wave guide lengths are disposed substantially in concentric relation.

5. A high frequency electronic device according to

claim 3, wherein the wave guide lengths comprise parts of a spirally wound wave guide.

6. A high frequency electronic device according to claim 3, wherein the wave guide lengths comprise parts of a helically wound wave guide.

7. A high frequency electronic device according to claim 3, wherein said electrodes are disposed in parallel planes, and the wave guide lengths are disposed between said planes.
